UNITED STATES PATENT OFFICE

118,272

DESIGN FOR A COMBINED BAGGAGE RACK AND LIGHTING FIXTURE OR SIMILAR ARTICLE

Christian M. Verhagen, Elkhart, Ind., assignor to
The Adlake Company, a corporation of Illinois

Application October 12, 1936, Serial No. 65,266

Term of patent 14 years

To all whom it may concern:

Be it known that I, Christian M. Verhagen, a citizen of the United States of America and a resident of Elkhart, county of Elkhart and State of Indiana, have invented a new, original, and ornamental Design for a Combined Baggage Rack and Lighting Fixture or Similar Article, of which the following is a specification, reference being had to the accompanying drawing, forming a part thereof, wherein

Fig. 1 is a perspective view of a combined baggage rack and lighting fixture showing my new design and illustrating a plurality of the units in assembled relation;

Fig. 2 is a front elevational view of one of the units;

Fig. 3 is a bottom plan view of Fig. 2; and
Fig. 4 is a sectional view taken on the line 4—4
of Fig. 2.

The design forming the subject matter of the present invention is for a combination baggage rack and lighting fixture of indeterminate length, and the design is repeated throughout this length.

In Figs. 2 and 3, a single unit only is indicated in solid lines, the broken lines indicating the continuation of the fixture.

I claim:

The ornamental design for a combined baggage rack and lighting fixture or similar article, substantially as shown and described.

CHRISTIAN M. VERHAGEN.
